MAIL HANDLING APPARATUS

Adelard F. Martel, San Mateo, Calif., assignor of
one-half to George W. Gates, Burlingame,
Calif.

Application June 21, 1932. Serial No. 618,499

3 Claims. (Cl. 258—1)

This invention relates to improvements in mail handling apparatus and more particularly to airplane loading and unloading means.

The principal object of the invention is to 5 pick up and discharge articles from air craft while in flight.

Another object is to speed up the air service by 10 eliminating the time loss occasioned by landing the air craft to receive and discharge its load of mail, merchandise, fuel, etc.

Another object is to automatically exchange 15 the incoming and outgoing portions of the load simultaneously.

Another object is to minimize the necessary 20 maneuvering of the air craft in receiving and discharging its load.

A further object is to render the apparatus 25 simple and inexpensive in construction and reliable and safe in operation.

20 Other objects and advantages will appear as the description progresses.

In this specification and the accompanying 30 drawings, the invention is disclosed in its preferred form. It is, however, to be understood 25 that it is not limited to this form because it may be embodied in other forms without departing from the spirit of the invention as defined in the claims following the description.

In the accompanying two sheets of drawings: 35 Fig. 1 is a plan view of an air mail loading apparatus constructed in accordance with this invention.

Fig. 2 is a front elevation of the same.

Fig. 3 is an enlarged detail view, looking from 40 beneath, of the latch for attaching the carrier of the outgoing mail bags to the pick up cable of the air craft.

Fig. 4 is a horizontal section showing the 45 means by which the mail bag carrier is detachably mounted on its bracket before being picked up by the pick up cable.

Fig. 5 is a side elevation partly in vertical 50 section of the automatic mail releasing apparatus just before being engaged by the outgoing carrier.

Fig. 6 is a fragmentary vertical section of the 55 dumping apparatus after the load has been discharged.

Fig. 7 is an elevation view partially in vertical 60 section of the resilient cushioning means interposed in the pick up cable.

In detail, the construction illustrated in the 65 drawings, referring more particularly to Fig. 1, comprises the angularly disposed guide rails 1—1 having their outer ends mounted at the tops of the posts 2—2 and suitably braced thereto at 3.

The opposite ends of the rails are supported on the posts 4—4 and terminate adjacent the restricted opening 5 therebetween, leading into the tapering throat 6 cut in the carrier disk 7. The flange 8 depends from the periphery of the disk 60 7 and has the slots 9—9 cut therethrough laterally to the throat 6.

The bracket 10 has the upstanding arcuate flange 11 thereon and is pivoted at 12 on the base 13 mounted at some distance from the 65 ground on top of the rigid pole 14. The inter-spaced pins 15—15 are mounted in the flange 11 and project laterally therefrom and are adapted to engage through the slots 9—9 to detachably mount the carrier disk 7 on the bracket 10. 70

The outgoing mail bags x have the rings x' closing their necks and are adapted to be hung on the hooks 17—17 fixed to the flange 8 of the disk 7 at intervals. The flat springs 18 are fixed to the top of the disk 7 and expand against the 75 ends of the hooks 17 to retain the rings x' in place within the hooks.

The latch 19 extends across and closes the entrance of the throat 6 and is pivoted on the pin 20 within the housing 16. The arm 21 extends 80 angularly from the latch 19 and is urged against the stop 22 by the spring 23 encircling the pin 20 and expanding between the housing 16 and the arm 21. The latch 19 thus resiliently swings 85 inward to admit the pick up cable into the throat 6 but engages against the stop 22 to prevent its withdrawal.

The bent over lug 24 is struck up from the end 90 of the throat 6 to present a smooth surface and minimize chafing of the pick up cable. The central portion of the carrier is bulged upward forming the spheroidal dome 7' to cooperate with the mail loading means as is later more fully described.

The pick up cable 25 is trailed from the air 95 craft, and has the automatic releasing apparatus suspended from its lower end. This apparatus consists of the rod 26 having the integral eyelet 27 provided at its upper end to receive the knotted end of the cable.

The lower end of the rod is bifurcated at 28 100 and has the clamps 29, 30 pivoted therein on the bolt 31. If desired, the clamp 30 can be formed of two congruent flat members pivoted on opposite sides of the clamp 29 as shown at 32 to 105 insure the proper operation of the clamps. In the closed position shown in Fig. 5 the jaws 33, 34 of these clamps overlap each other to securely grip the ring y' having the mail bags y suspended therefrom.

The latch arms 36, 37 extend upwardly from the clamps 29, 30 and have the undercut notches 38, 39 therein near their upper ends. The sleeve 40 encircles the central portion of the rod 26 and has the vertical slots 41, 42 therethrough on opposite sides near its lower end. The lower edges of the slots are arranged to engage under the notches 38, 39 in the latch arms to lock the clamp in closed position. The rod 26 has the transverse slot 43 therethrough to receive the inwardly projecting ends of the latch arms when the clamp is in the closed position.

The pin 44 is fixed in the rod 26 and projects laterally therefrom through the slot 45 in the sleeve 40. The spring 46 contracts between the pin 44 and the lug 47 struck outwardly from the sleeve 40 and urges the sleeve upward to resiliently engage the ends of the slots 41, 42 in the notches 38—39 in the latch arms.

The spheroidal trip 48 is rigidly mounted at the upper end of the sleeve 40 and is adapted to engage under the dome 7' of the carrier disk to operate the sleeve 40 as is later more completely described. The lower end of the sleeve 40 is arranged in juxtaposition to the inclined edges 49—50 to cooperate therewith to open the clamp when the sleeve 40 is operated.

The cushioning of the pick up cable 25 is accomplished by the helical spring 51 enclosed within the cylinder 52. This spring expands between the end of the cylinder 52 and the plunger 53 mounted upon the end of the rod 54. The ends of the pick up cable 25—25" are fixed to the cylinder 51 and the end of the rod 54, respectively. Pressure exerted on the end 25" compresses the spring 52 before being transmitted to the opposite end 25' of the cable.

The apparatus operates substantially as follows: The mail bags *y* are suspended on the ring *y'* held in the clamp jaws 33, 34 and the automatic mail bag dumping assembly is lowered from the airplane at the end of the cable 25. The airplane is then maneuvered to enter the cable between the guide rails 1—1. The cable travels in the direction of the arrow shown in Fig. 1 and is guided by the rails 1 into the entrance of the throat 6. The latch 19 yields before the oncoming cable and admits it into the throat. When the cable passes the end of the latch 19, the spring 23 snaps the latch back into operative position confining the cable against rebound in the throat 6 between the lug 24 and the latch.

As the cable advances against the lug 24, the bracket 10 swings outward on its pivot 12 and brings the retaining pins 15 to a position to the rear with respect to the direction of movement of the cable. The carrier disk 7 then disengages from the pins 15 and slides off the bracket 10. It will be noted that disengagement of the disk 7 can not be accomplished until the bracket 10 is swung outward to bring the pins into a position to the rear. This assures the cable 25 properly tripping the latch 19 and becoming engaged within the throat 6 before the carrier disk can be disengaged.

The disk 7 descends on the cable 25 and snugly engages its spheroidal dome 7' over the rounded surface of the trip 48 and the carrier is maintained in substantially horizontal position thereon. The weight of the carrier 7 and the mail bags *x* attached thereto, depresses the trip 48 and the sleeve 40 against the tension of the

spring 46. This removes the ends of the slots 41, 42 from engagement with the notches in the latch arms 36, 37 and permits the weight of the mail bags *y* to force open the clamp jaws 33, 34 and drop therefrom to the ground.

The lowering of the sleeve 40 with respect to the rod 26 advances its lower end into contact with the inclined surfaces 49—50 as shown in Fig. 6. This positively insures the proper opening of the clamp jaws in the event of the weight of the mail bags *y* being insufficient to effect the opening of the clamp.

After the operation is completed, the cable 25 is drawn up into the airplane and the mail bags *x* and the carrier 7 are removed by the operator. The mail bags to be deposited in the succeeding station are then placed in the clamp jaws 33—34 and the sleeve 40 is manually depressed and the notched latch arms 36, 37 reengaged in the slots 41—42. The apparatus is then lowered from the airplane and the operation repeated.

Having thus described this invention, what is claimed and desired to be secured by Letters Patent is:

1. An apparatus of the class described comprising a stationary base, a carrier detachably mounted on said base and having an open throat therein, a cable adapted to engage in said throat to pick up said carrier, means for guiding said cable into said throat, a latch mounted on said carrier and adapted to confine the cable within said throat, a rod suspended from the lower end of said cable, a pair of clamp members pivoted at the lower end of said rod, notched latch arms extending from said clamp members, a sleeve slidably engaging said rod and having slots therein adapted to engage said latch arms, resilient means urging said slots into engagement with said latch arms, and a trip fixed to said sleeve and adapted to be impinged upon by said carrier to disengage said slots from said latch arms.

2. An apparatus of the class described comprising a stationary base, a bracket pivoted on said base, pins set in said bracket, a flanged carrier detachably engaging said pins and having an open throat therein, a cable adapted to engage in said throat to pick up said carrier, means for guiding said cable into said throat, a latch mounted on said carrier and adapted to confine the cable in said throat, a rod suspended from the lower end of said cable, a clamp mounted on said rod, a sleeve encircling said rod and arranged to latch said clamp in closed position, and a trip mounted on said sleeve and adapted to be impinged upon by said carrier to disengage said sleeve from said clamp.

3. An apparatus of the class described comprising a stationary base; a carrier detachably mounted on said base and having an open throat therein; a trailing cable adapted to engage in said throat to pick up said carrier; a rod suspended from the lower end of said cable; clamp members pivoted on the lower end of said rod; latch arms extending from said clamp members and having undercut notches therein; locking means slideable on said rod and engageable with the notches in said latch arms; a trip operatively connected to said locking means and adapted to be impinged upon by said carrier to disengage said locking means from said latch arms.

ADELARD F. MARTEL.
